TISSUE DISPENSER

Ethel Leo Humphrey, Brady, Tex.

Application August 22, 1955, Serial No. 529,813

1 Claim. (Cl. 206—57)

The present invention relates to new and useful improvements in tissue dispensers and has for its primary object to provide, in a manner as hereinafter set forth, novel means for holding a supply of paper tissues on the cowl of a motor vehicle for convenient use.

Other objects of the invention as to provide a tissue dispenser of the aforementioned character which will be comparatively simple in construction, durable, compact, attractive in appearance and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view, showing a tissue dispenser constructed in accordance with the present invention in position on a motor vehicle;

Figure 2 is a top plan view with a portion of the cover broken away; and

Figure 3 is a vertical sectional view through the device, taken substantially on the line 3—3 of Figure 1.

Referring now to the drawing in detail, it will be seen that the embodiment of the invention which has been illustrated comprises a substantially rectangular container of suitable material which is designated generally by reference character 5. Hingedly mounted at 6 on the container 5 is a cover 7.

The container 5 is adapted to be mounted on the usual instrument panel or cowl 8 of a motor vehicle 9 behind the windshield 10. Toward this end, the bottom 11 of the container 5 has secured therebeneath a plurality of vacuum or suction cups 12. Bolts 13 secure the suction cups 12 on the container 5, said bolts passing through openings provided therefor in the bottom 11 of said container and having threaded thereon retaining nuts 14.

2

The container 5 is adapted to snugly receive and retain a conventional dispensing carton 15 of tissues. Toward this end, the walls of the container 5 have their upper portions folded inwardly and downwardly to provide a bead 16 for retaining the carton 15 in position. It will be noted that the carton 15 is engaged beneath the bead 16.

It is thought that the use of the invention will be readily apparent from a consideration of the foregoing. 10 Briefly, the container 5 is positioned on the instrument panel or cowl 8 of the vehicle and secured through the medium of suction cups 12. The dispensing carton 15 is then inserted in the container 5 and engaged beneath the bead 16. With the hinged cover 7 in open position, the tissues may be removed in an obvious manner from the carton 15. The bead 16 anchors the carton 15 in the container 5 when the tissues are pulled or withdrawn from said carton.

The foregoing is considered as illustrative only of the 20 principles of the invention. Further, since numerous modifications and changes will readily occur to those skilled in the art, it is not desired to limit the invention to the exact construction and operation shown and described, and accordingly all suitable modifications and 25 equivalents may be resorted to, falling within the scope of the invention as claimed.

What is claimed as new is as follows:

A tissue dispenser comprising, in combination, a substantially rectangular container including a bottom and a hinged cover, an inwardly and downwardly folded bead on the upper portion of said container, a sheet dispensing carton, comprising a resilient bottom, removably mounted in the container and engaged beneath the bead for retention thereby, suction cups mounted beneath the container bottom for removably securing the container on a support, bolts on the suction cups extending upwardly through said container bottom into the container, and retaining nuts threaded on said bolts and engaged beneath the carton bottom for bending and tensioning same for yieldingly urging the carton upwardly beneath the bead.
